WRITER COMPANY, OF NEW YORK, N. Y., A CORPORATION OF DELAWARE.

TYPE-WRITING MACHINE.

1,151,730.

Specification of Letters Patent. Patented Aug. 31, 1915.

Application filed November 22, 1913. Serial No. 802,337.

To all whom it may concern:

Be it known that I, STEPHEN T. SMITH, a citizen of the United States, residing in Stamford, in the county of Fairfield and 5 State of Connecticut, have invented certain new and useful Improvements in Type-Writing Machines, of which the following is a specification.

This invention relates to typewriting machines, and particularly to means for increasing the capacity of the machine for writing a variety of characters.

According to this invention, a paper carriage is shiftable from one set of types to another set, each set having its own keys. The type sets may be placed side by side, and the carriage may run upon a multiple-length track, which enables it to coöperate with either set of types at the will of the operator. Thus the number of types for use with a single paper carriage may be doubled, and the capacity of the machine for writing a variety of types increased accordingly. For instance, one set of types or keys 20 could be such as are ordinarily employed for writing the English language, and the other set of types or keys could be used for writing Greek or another language; or both sets of types could be English, one being a 25 roman style, and the other being an italic style, so that the user of the machine could emphasize words by shifting the paper carriage over to the other side of the machine, and writing words in italics. Or one key- 30 board could be devoted to a standard language, such as English, German, French, Spanish, etc., while the other side could have both a Greek alphabet and another alphabet, or perhaps a set of special characters. 35 If it be desired to use the machine for writing Japanese, one keyboard could be devoted to characters used in writing names, while the other keyboard could be devoted to special characters used in any branch of 40 business.

In the preferred manner of carrying out the invention, there may be employed two Underwood front-strike machines, which may be placed side by side and fixed together, the usual carriage tracks being replaced by multiple-length front and rear rails; and a single carriage may run on said rails and be movable from one part of the double machine to the other. The invention

is not, however, limited to the use of two 55 keyboards, as it is obvious that as many keyboards and sets of types may be employed as desired, and carriage tracks may be employed of sufficient length to permit the carriage to be shifted along the rails into co-operation with any desired set of types. 60 Each set of types may therefore be provided with its own keyboard, its own ribbon mechanism, including the usual Underwood ribbon-vibrator, and its own carriage-escapement devices, which coöperate with the escapement rack upon the carriage. Each keyboard may also have its own shift-key mechanism for writing upper and lower case characters; and although this shift-key 65 mechanism usually employs a shift rail to lift the platen of the typewriter, still the platen-frame roll which is engaged by said shift rail does not ordinarily rest upon the rail, but occupies a position a trifle above 70 the same; so that the carriage may be transferred from one type system to the other independently of the shift rails, when both of the latter are in their lower positions, or 75 both in their upper positions; in which positions they may be held by the usual shift-lock mechanism. Each section of the multiple machine may also be provided with the usual back-spacer, and generally with other typewriting appurtenances, so that when 80 the operator is using the carriage with either set of types, he may operate in the same 85 manner as with an ordinary machine.

In the present instance, the left-hand margin gage is employed at the left-hand 90 of one type system, and the right-hand margin gage is employed at the right-hand 95 of the other type system, this provision being useful for ordinary purposes; other margin-gage devices being preferably omitted to permit the carriage to be shifted from one type system to the other.

Other objects and advantages will hereinafter appear.

In the accompanying drawings, Figure 1 100 is a perspective plan of one form of multiple keyboard and type-system machine made in accordance with the present invention. Figs. 2, 3 and 4 show different varieties of types which may be used in the Fig. 105 1 machine. Fig. 5 is a sectional elevation taken about centrally of either of the main portions of the machine seen at Fig. 1.

In practising the invention in the form illustrated, the frameworks 1, 2 of two Underwood front-strike typewriting machines may be rigidly secured by fasteners 2^a, Fig. 5, upon a common base 3; and they may also be rigidly joined by a rear carriage rail 4 and a front carriage rail or structure 5, each of which rails extends unbrokenly from the left-hand end of the frame 1 to the right-hand end of frame 2, each forming a single multiple-length track. Upon these rails may travel a carriage 6, which is an Underwood typewriter carriage of the usual construction. This carriage has front rolls 6^a to run in the groove of track 5, and collars 6^b to clasp rear guide-rail 4. The carriage usually has a feed rack 7, releasable by a key 8, and normally in mesh with a pinion 9, which is connected to an escapement wheel 10, the latter operable by type keys 11; said keys being mounted on levers 12 and connected by sub-levers 13 to type bars 14, which have heels 15 to thrust backwardly a universal bar 16, mounted on idle links 17 and adapted to strike a dog rocker 18, which controls the movements of the escapement wheel 10.

Assuming that the paper carriage or platen-carriage 6 is in the right-hand writing-field, as seen at Fig. 1, the operator manipulates the keys 11 to strike the types 19 upwardly and rearwardly against a platen 20, and the platen-carriage feeds along step-by-step in the usual manner; the ribbon 21 being mounted upon the usual spools 22 and operating in the usual manner. The operation of writing may proceed in the same manner as usual with typewriting machines; and if at any time the operator wishes to use the types 23 in the left-hand system (which may be italics, for example), he depresses the carriage-release key 8, and then shifts the carriage along the front and rear tracks 5, 4, until the index 24 on the carriage (which has heretofore been coöperating with scale 25), coöperates with scale 26 on the frame 1; the rack 7 becoming disengaged from escapement pinion 9 and engaged to escapement pinion 27 on the left-hand machine; the operation of all the left-hand side mechanism by the keys 28 corresponding to the operation effected by the keys 11 of the right-hand keyboard. The carriage is connected by a long strap 29 to a spring barrel 30, which, by making a plurality of revolutions, is able to propel the carriage for its letter-feeding movements throughout its range of travel on the long rails 4, 5. The carriage now feeds under the control of the keys 28, in the same manner as it formerly made letter-feeding movements under the control of the escapement wheel 10 and keys 11; said wheel 10, however, being motionless while the carriage is under the control of escapement wheel 31.

At Fig. 2 is shown a type 32, having thereon characters in two languages 33 and 35, either of which may be called into use by a shift key 35^a and all of the type bars 36 in this frame may have such type characters as are seen at 33 and 34, one set of characters being on the upper-case shift, and the other set of characters being on the lower-case shift. Or all of the type bars 36, as at Fig. 3, may be provided with upper-case and lower-case italic types, to match the roman characters on the type bars 14 seen at Fig. 4. The shift-keys 35, 37 in the two keyboards are for temporary use, either of them lifting up the platen 20 and platen frame 38, and each key being held depressed by the finger while the operator manipulates the type keys. The keyboards are also provided with permanent or locking shift-keys 39, 40, which lock the platen and platen frame in the upper shift position; and as already explained, the paper carriage may be adjusted freely back and forth between the two keyboards when both shift keys 39, 40 are either down or up, without liability of the shift roll 41 on the platen frame striking against the end of either of the shift rails 42, which are controlled by the keys 35, 37, 39, 40; a part of the connection between said shift rail and the keys being seen at 43. At the right of the right-hand frame 2 is the usual adjustable margin gage 44 for limiting the return stroke of the carriage, and determining the beginning of a new line. The usual left-hand margin gage is omitted from the frame 2, in order to permit the shifting of the carriage 6 across to the frame 1; and the usual right-hand margin gage is omitted from the frame 1 for the same reason. Frame 1, however, carries the usual adjustable left-hand margin gage 45 for ringing the bell and locking the keys. If desired, the left-hand keyboard may write the standard language, so that the operator can have the advantage of the use of the margin gage 45 for the bulk of his work, and the keyboard and type bars in the frame 2 may be made special and hence infrequently used, so that the omission of the left-hand margin gage will not be an objection; and in this case the usual right-hand margin-gaging device may be used on frame 1, such gaging device usually being constructed to permit the carriage to run to the right past the gage when desired. This permits the carriage to be shifted over to frame 2. Such gaging device would offer no obstacle to the shifting of the carriage from frame 2 to frame 1. Each keyboard may of course have its own word-spacing key, as indicated at 46 and 47; and, in general, each section of the machine, when co-operating with carriage 6, may be a complete typewriter in itself.

Variations may be resorted to within the 130

scope of the invention, and portions of the improvements may be used without others.

Having thus described my invention, I claim:

5. 1. A typewriting machine comprising a plurality of keyboards, a plurality of systems of alphabetical types, the types in one system being operable independently of those in the other system, and a paper-carrier adjustable to coöperate with either type-system.

15. 2. A typewriting machine comprising a plurality of type-systems, each system having its individual printing center, and the types in one system being operable independently of those in the other system, and a paper-carriage adjustable to either printing center.

20. 3. The combination of a plurality of type-systems, the types in one system being characteristically different from the types in the other system, the types in each of the systems mounted to print at a common point, and the types in one system being operable independently of those in the other system, and a platen, having a single printing field, adjustable to enable its printing field to coöperate with either type system.

25. 4. The combination of a plurality of type-systems, each having its own printing point, and the types in one system being operable independently of the types in the other system, and a platen adjustable to coöperate with either type-system, said platen having letter-feeding movements when in coöperative relation with either type-system.

30. 5. A typewriting machine comprising a plurality of keyboards, a plurality of type-systems operatively associated with said keyboards, the types in each system directly operable independently of one another by the keys in the associated keyboard, and the types in one system being operable independently of the types in the other system, a paper-carriage, and a track along which the paper-carriage may move to enable it to coöperate with either type-system.

35. 6. A typewriting machine comprising a plurality of keyboards, a plurality of sets of types individually operable by the keys in said keyboards, the types in each set being operable independently of those in the other set, a paper-carriage, a track along which the paper-carriage may move to enable it to coöperate with either set of types, and a spring for propelling said carriage throughout its range of travel relatively to both sets of types.

40. 7. A typewriting machine comprising a plurality of type-systems, a keyboard for each type-system, the types in each system being individually operable independently of the types in the other system, a paper-carriage, a spring to propel said carriage throughout its range of travel along both

type-systems, and two letter-feeding mechanisms, one for each of said keyboards, said letter-feeding mechanisms operable alternatively, to enable each keyboard to control the carriage when the latter is coöperating with the associated type-system.

45. 8. A typewriting machine comprising two sets of types, each having its own printing center, the types in each set being individually operable independently of the types in the other set, a platen, a carriage to enable relative shifting between the platen and the type-sets, to enable the platen to coöperate with either set of types to the exclusion of the other set, said carriage having letter-feeding movements when in coöoperative relation to each set of types, and two inking ribbons, one for each set of types, each ribbon being actuatable at the individual operations of the types in its associated set and independently of the other ribbon.

50. 9. A typewriting machine comprising two frames, two type-operating mechanisms, each including a keyboard, one type-operating mechanism in each frame, a carriage, and a carriage track along which said carriage is shiftable from a position to coöperate with one type mechanism to a position to coöperate with the other type mechanism, said carriage having letter-feeding movements when in coöoperative relation to either type-system, and said track joining said frames to permit the carriage while coöoperating with one type mechanism to run over onto the other frame, whereby compactness of structure is secured; each type mechanism comprising types operable individually and independently of the types of the other type mechanism.

55. 10. A typewriting machine, comprising a plurality of keyboards; a plurality of type-systems, one for each keyboard, the types in each system having upper and lower case characters and being individually operable by their connected keyboard independently of the types in the other system; and a paper-carrier adjustable to coöperate with either type-system, said paper-carrier having letter-feeding and case-shifting movements when in coöoperative relation to each system of types.

60. 11. A typewriting machine, comprising a plurality of keyboards; a plurality of type-systems, one for each keyboard, the type in each system having upper and lower case characters and being individually operable by their connected keyboards independently of the types in the other system; a carriage adjustable from a position to coöperate with only one of said type-systems, to a position to coöperate with only the other type-system, said carriage having letter-feeding movements when in coöoperative relation to either type-system; a platen frame and carriage; and a platen mounted in said frame.

frame, said frame having case-shifting movements when in coöperative relation to either type-system.

12. A typewriting machine, comprising a plurality of keyboards; a plurality of type-systems, one for each keyboard; a paper-carrier adjustable to coöperate with either type-system, said paper-carrier having letter-feeding movements when in coöperative relation to either type-system; a separate letter-feeding scale associated with each type-system; and a single indexing device on said paper-carrier to coöperate with both scales.

13. A typewriting machine provided with a system of types for one language, a system of types for a different language, the types in each system being individually impresible independently of the types in the other system, each system having its own printing center, a carriage shiftable for bringing either system into use at will in writing a single line, and two sets of keys, one for each of said systems of types.

14. In a typewriting machine, the combination with a plurality of type systems, each having its own printing point or center, of a platen movable into positions to coöperate with either type system, and a letter-feeding mechanism for each type system, each letter-feeding mechanism operable to effect letter-feed movements of the carriage while in coöperative relation to its type system, and inoperative to control the carriage while the latter is in coöperative relation to the other type system.

15. In a typewriting machine, the combination with a plurality of type systems, each having its own printing point or center, of a keyboard for each type system, a platen movable into positions to coöperate with the type systems alternatively, and an individual letter-feeding mechanism for each keyboard operable to effect letter-space movements of the carriage when in coöperation with the corresponding type system.

16. A typewriting machine comprising a plurality of keyboards, a plurality of type systems, a paper carriage, a multiple length track along which the paper carriage may move to enable it to coöperate with either type system, a letter-feeding mechanism actuated by the keys of one keyboard to effect letter-feed movements of the carriage when in coöperative relation to the type system operated by said keys, and a letter-feed mechanism operable by the keys of the other keyboard to effect letter-feed movements of the carriage when in coöperative relation to the other type system.

17. In a typewriting machine, the combination with machine frames mounted side by side, each frame having mounted thereon a type system and a keyboard comprising a set of keys for actuating the types of said

system, of a multiple length track extending across said frames, a paper carriage mounted on said track movable therealong into coöperative relation to either type system, and letter-feed mechanism controlling the letter-feed advance of the carriage while in coöperative relation to both systems.

18. In a typewriting machine, the combination with machine frames mounted side by side, each frame having mounted thereon a type system and a keyboard comprising a set of keys for actuating the types of said system, of a multiple length track extending across said frames, a paper carriage mounted on said track movable therealong into coöperative relation to either type system, and letter-feed mechanisms each individually operable by the keys of one set to control the letter-feed advance of the carriage while in coöperative relation to the corresponding type system, and inoperative to control the carriage while the latter is in operative relation to the other type system.

19. The combination with a plurality of type systems, of a carriage movable into coöperative relation to either type system, a letter-feed rack on said carriage, and a separate escapement mechanism associated with each type system, each of said escapement mechanisms comprising a pinion to engage said rack and control the advance of the carriage while the latter is in position to coöperate with the corresponding type system.

20. In a typewriting machine, the combination with type systems placed side by side and each having its own printing point or center, of a double length track, a carriage mounted to travel thereon, and movable thereon out of printing relation to one type system into printing relation to the other type system, a letter-feed rack on the carriage, and an escapement mechanism associated with each type system, each escapement mechanism comprising a pinion running in mesh with said rack and controlling the letter-feed movements of the carriage while in coöperative relation to the corresponding type system, said rack being beyond the range of one pinion while in driving relation to the other pinion.

21. A typewriting machine comprising a plurality of keyboards, a plurality of type systems operable in alternation, and a paper carrier adjustable to coöperate with either type system, the paper carrier throughout its range of movement in coöperative relation to either type system being out of coöperative relation to the other type system.

22. In a typewriting machine, the combination with a plurality of separately mounted type systems each having its own printing center, one type system being remote from the other and each type system operable independently of the other, of a platen, means, including a carriage, to enable said platen to

- coöperate with either type system, and letter-feeding means to control said carriage while said platen is coöperating with said type systems.
- 5 23. The combination of two alphabetical type systems, each system having its own separate printing point and each type-system operable independently of the other, a carriage movable to bring either system into 10 play, and means for letter-feeding the carriage when writing each alphabet.
24. The combination of two systems of alphabetical types, said systems placed side by side and each having its own separate 15 printing point and each type-system operable independently of the other, a carriage movable from side to side to bring either alphabet into use, and means for feeding the carriage when each type system is being 20 used.
25. The combination of a plurality of alphabetical type systems placed side by side and each having its own separate printing point and each type-system operable independently of the other, a carriage, a multiple-length track for said carriage, and letter-feeding means coöoperative with said carriage when each system is being used.
26. The combination of a plurality of 30 alphabetical type systems placed side by side and each having its own separate printing point, a carriage, a multiple-length track for said carriage, letter-feeding means coöoperative with said carriage when each system is being used, and a plurality of separate keyboards.
27. The combination of two systems of types, one for one language, and the other for another language, a carriage shiftable in 40 the general direction of its letter-feeding movements, to bring either system of types into use, and letter-feeding means to coöperate with said carriage when each language is being written.
- 45 28. The combination of two front-strike writing mechanisms placed side by side and fixed together and having a single carriage, multiple-length front and rear rails connecting said mechanisms and supporting said carriage, and letter-feeding means to coöperate with said carriage; each of said mechanisms operable independently of the other.
29. A multiple typewriting machine comprising a plurality of separated type-systems, carriage tracks of sufficient length to permit the carriage to be shifted into coöperation with any desired set of types, and means for letter-feeding the carriage at 55 the operation of the types.
30. A multiple typewriting machine comprising a plurality of separated type systems, a carriage, carriage tracks of sufficient length to permit the carriage to be shifted into coöperation with any desired set of types, 60 and means for letter-feeding the carriage at the operation of the types.
- types, and letter-feeding means having coöperation with all the types; each set of types having its own ribbon mechanism and its own carriage escapement devices.
31. A multiple typewriting machine comprising a plurality of separated type-systems, a carriage, carriage-feeding devices, and carriage tracks of sufficient length to permit the carriage to be shifted into coöperation with any desired set of types, each 70 set of types having its separate keyboard, and each keyboard also having its own shift key.
32. The combination of two front-strike writing machines placed side by side and fixed together, a single carriage, multiple-length front and rear rails connecting said machines and supporting said carriage, letter-feeding devices for coöperating with said carriage, to enable it to coöperate with each 80 of said machines, a left-hand margin gage for the left-hand type system, and a right-hand margin gage for the other type system.
33. The combination of two keyboards, two sets of alphabetical types, a platen movable into position to coöperate with either set of types, and two letter-feeding mechanisms for said platen, the latter being controllable by either letter-feeding mechanism 90 independently of the other.
34. The combination of two keyboards, two sets of alphabetical types, a platen, a carriage for effecting relative movement between said platen and said sets of types, to enable either set to coöperate with said 100 platen, a letter-feeding escapement mechanism operable by one of said keyboards, and a letter-feeding escapement mechanism operable by the other of said keyboards, the carriage being controllable by either escapement mechanism independently of the other.
35. A typewriting machine comprising a plurality of keyboards, a plurality of sets of alphabetical types, the types in one set being operable independently of and characteristically different from those in the other set, a platen, a carriage shiftable to enable either set of types to coöperate with said platen, and devices operable by the keyboards to control the relative letter-feeding 110 movement between the platen and the type-sets.
36. A typewriting machine comprising a plurality of keyboards, the keys in one keyboard bearing characters characteristically different from those in the other keyboard, a plurality of sets of types, one set for each of said keyboards, the types in each set capable of being individually impressed independently of the types in the other set, a 120 platen, and a carriage shiftable to enable either set of types to coöperate with said platen, said carriage having letter-feeding movements during its period of coöperation with the types in each of said sets.

37. A typewriting machine, comprising a plurality of keyboards, each including a shift key, said shift keys being operable independently of each other; a plurality of type-systems, one for each keyboard, the types in each system including characters brought into use at a case-shifting operation, and being operable individually and independently of the types in the other system; and a paper-carrier adjustable to co-operate with either type-system and having case-shifting movements controlled by the corresponding shift key during its period of co-operation with either type-system.
38. A typewriting machine, comprising a plurality of keyboards, each including a shift key, said shift keys being operable independently of each other; a plurality of type-systems, one for each keyboard, the types in each system including characters brought into use at a case-shifting operation, and being operable individually and independently of the types in the other system; a carriage shiftable from a position to co-operate with only one of said type-systems to a position to co-operate only with the other type-system; a platen frame on said carriage; and a platen mounted in said frame, said frame having case-shifting movements controlled by the corresponding shift key during the period of co-operation of said carriage with either type-system.
39. A typewriting machine provided with a system of type-bars having types for one language, all mounted to strike at a single impression point, a second system of type-bars having types for a different language, all mounted to strike at another impression point, and shiftable means for bringing either system of type-bars into use at will in writing a single line; the type-bars in each system operable independently of those in the other system.
40. A typewriting machine comprising in combination a plurality of type-systems, each system having its individual printing center, the types in one system being operable independently of the types in the other system, a plurality of keyboards, one for each type-system, a paper-carriage adjustable to either printing center, and letter-feeding mechanisms individual to the two type-systems, and operable by said keyboards to control the carriage.
41. A typewriting machine comprising in combination a plurality of type-systems, each system having its individual printing center, the types in one system being operable independently of the types in the other system; a plurality of keyboards, one for each type-system, a paper-carriage adjustable to either printing center, and letter-feeding mechanisms individual to the two type-systems, and operable by said keyboards to control the carriage; said carriage having a single rack for coaction with either of said letter-feeding mechanisms.
42. A typewriting machine comprising in combination a plurality of type-systems, each system having its individual printing center, the types in one system being operable independently of the types in the other system, a plurality of keyboards, one for each type-system, a paper-carriage adjustable to either printing center, and letter-feeding mechanisms individual to the two type-systems, and operable by said keyboards to control the carriage; said carriage having a single rack for coaction with either of said letter-feeding mechanisms, said carriage being connectible to either of said letter-feeding mechanisms and being provided with a release key for disconnecting it at will from either of said letter-feeding mechanisms.
43. A typewriting machine, comprising a plurality of keyboards; a plurality of systems of alphabetical types, the types in one system being operable independently of those in the other system; and a paper-carrier adjustable to co-operate with either type-system, said paper-carrier having letter-feeding movements when in co-operative relation to either type-system.
44. A typewriting machine, comprising a plurality of keyboards; a plurality of systems of alphabetical types, one for each keyboard, each system having its individual printing center, the types in each system having upper and lower case characters and being operable by their connected keyboard independently of the types in the other system; and a paper-carrier adjustable to co-operate with either type-system, said paper-carrier having letter-feeding and case-shifting movements when in co-operative relation to either type-system.
45. A typewriting machine, comprising a plurality of type-systems, each system having its individual printing center and the types in one system being operable independently of those in the other system; and a paper-carriage adjustable to either printing center, said paper-carriage having letter-feeding movements when in co-operative relation to the types in either system.
46. A typewriting machine, comprising a plurality of keyboards; a plurality of type-systems, the types in one system being operable independently of those in the other system; a paper-carrier adjustable to co-operate with either type-system; and mechanism for effecting letter-feeding movements of said paper-carrier during its period of co-operation with either type-system.
47. A typewriting machine, comprising a plurality of keyboards; a plurality of type-systems, the types in each system having upper and lower case characters and the types in either system being operable inde-

pendently of those in the other system; a
paper-carrier adjustable to coöperate with
either type-system and having case-shifting
movements during its period of coöperation
5 with either type-system; and mechanism
for effecting letter-feeding movements of
said paper-carrier during its period of co-
operation with either type-system.
